UNITED STATES PATENT OFFICE

135,194

DESIGN FOR A FACEPLATE FOR A LEVELING INSTRUMENT

Samuel Aronoff, Dayton, Ohio

Application February 21, 1941, Serial No. 99,150

Term of patent 3½ years

To all whom it may concern:

Be it known that I, Samuel Aronoff, a citizen of the United States, residing at Dayton, in the county of Montgomery and State of Ohio, have invented a new, original, and ornamental Design for a Face Plate for a Leveling Instrument, of which the following is a specification, reference being had to the accompanying drawing, forming part thereof.

The figure is a plan view of the face plate for a leveling instrument, showing my new design.

The article is of no appreciable or substantial thickness.

The dominant feature of my design resides in the arrangement of the apertures in the face plate with respect to the horizontal principal axes of the aircraft design.

I claim:

The ornamental design for a face plate for a leveling instrument, as shown and described.

SAMUEL ARONOFF.
